UNITED STATES PATENT OFFICE.

CARRIE G. BURBANK, OF OAKLAND, CALIFORNIA.

DESIGN FOR A WASHSTAND.

Application filed November 26, 1928. Serial No. 29,031. Term of patent 14 years.

To all whom it may concern:

Be it known that I, CARRIE G. BURBANK, a citizen of the United States, and a resident of Oakland, in the county of Alameda and State of California, have invented a new, original, and ornamental Design for Washstands, of which the following is a specification, reference being had to the accompanying drawings, forming part thereof.

I claim:

The ornamental design for a washstand, substantially as shown.

CARRIE G. BURBANK.
